(22) Filed: **Jun. 3, 2014**

(57) **CLAIM**

The ornamental design for a vehicle, toy, and/or replicas thereof, as shown and described.

(30) **Foreign Application Priority Data**

DESCRIPTION

Dec. 4, 2013 (DE) 40 2013 101 224

This application contains subject matter related to the following co-pending U.S. design patent applications:

(51) **LOC (10) Cl. 12-08**

Application Ser. No. 29/462,848, filed Aug. 9, 2013 and entitled Vehicle, Toy, and/or Replicas Thereof;

(52) **U.S. Cl.**

Application Ser. No. 29/492,752, filed herewith and entitled "Front Bumper for a Vehicle";

USPC **D12/92**

Application Ser. No. 29/492,754, filed herewith and entitled "Rear Bumper for a Vehicle";

(58) **Field of Classification Search**

Application Ser. No. 29/492,755, filed herewith and entitled "Taillight for a Vehicle"; and

USPC D12/86, 90-92; D21/421, 433, 434;

296/181.1, 181.5

CPC B62D 35/00; B62D 25/00; B62D 25/06;

B62D 25/08; B62D 33/00

See application file for complete search history.

Application Ser. No. 29/492,756, filed herewith and entitled "Taillight for a Vehicle".
